UNITED STATES PATENT OFFICE.

CHARLES A. STUART, OF KENOSHA, WISCONSIN, ASSIGNOR TO SIMMONS COMPANY, OF KENOSHA, WISCONSIN, A CORPORATION OF DELAWARE.

DESIGN FOR A BEDSTEAD END.

56,633.

Specification for Design. Patented Nov. 16, 1920.

Application filed March 8, 1920. Serial No. 364,296. Term of patent 14 years.

To all whom it may concern:

Be it known that I, CHARLES A. STUART, a citizen of the United States, residing at Kenosha, in the county of Kenosha and State of Wisconsin, have invented a new, original, and ornamental Design for a Bedstead End, of which the following is a specification, reference being had to the accompanying drawing, forming part thereof.

The figure is a perspective view of the foot end of a bedstead embodying my new design.

The salient feature of this design is the shape of the corner posts, which are curved inwardly toward each other, the curve commencing substantially at a tangent to

the vertical, some distance above the bottom rail of the frame.

Other salient features of my new design are the central panel, substantially as described in my co-pending application No. 1964, and also the series of equi-spaced filler members interposed between the central panel and each corner post.

My design is of especial value where the frame members of the bedstead end frame are constructed of metallic tubing.

I claim:

The ornamental design for a bedstead end, substantially as shown and described.

CHARLES A. STUART.
